[57] **CLAIM**

The ornamental design for a unit for use with an emergency vehicle for storage and retrieval or remotely located emergency devices, as shown and described.

DESCRIPTION

FIG. 1 is a side perspective view of a unit for use with an emergency vehicle for storage and retrieval of remotely located emergency devices showing our new design;

FIG. 2 is a front elevational view thereof;

FIG. 3 is a rear elevational view thereof;

FIG. 4 is a side elevational view thereof;

FIG. 5 is a top plan view thereof; and,

FIG. 6 is a bottom plan view thereof.

The broken line showing of environmental structure in FIGS. 2, 3, 5 and 6 is for illustrative purposes only and forms no part of the claimed design.

FIG. 1

FIG. 2

FIG. 3

FIG. 4

FIG. 5

FIG. 6
